CLAIM

The ornamental design for a container infuser, as shown and described.

DESCRIPTION

FIG. 1 is a front perspective view from above of a first embodiment of a container infuser in accordance with the present invention;

FIG. 2 is a rear perspective view from below thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof.

FIG. 9 is a front perspective view from above of a second embodiment of a container infuser in accordance with the present invention;

FIG. 10 is a rear perspective view from below thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The dashed lines at the top of the container infuser depict portions of the container infuser that form no part of the claimed design. The dashed lines around the sidewall of the container infuser depict unclaimed surface indicia that form no part of the claimed design.
